UNITED STATES PATENT OFFICE

2,424,051

STARCH PAN ATTACHMENT FOR
CLOTHES WRINGERS

Claude E. Pickens, Ulysses, Kans.

Application September 20, 1944, Serial No. 554,978

1 Claim. (Cl. 91—31)

1

The present invention relates to new and useful improvements in laundering equipment and more particularly to a starch pan attachment for a clothes wringer by means of which the clothes may be starched in the pan and then fed through the wringer and the excess liquid again collected in the pan for future use.

An important object of the present invention is to provide a starch pan attachment for a clothes wringer embodying means for easily and quickly attaching the pan in position under the wringer and which at the same time is simple and of practical construction, efficient and reliable in use and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view of a clothes wringer showing the starch pan in position under the wringer.

Figure 2 is an edge elevational view of the wringer showing the starch pan in position for use.

Figure 3 is a fragmentary sectional view taken substantially on a line 3—3 of Figure 2, and

Figure 4 is a fragmentary sectional view taken substantially on a line 4—4 of Figure 1.

Referring now to the drawings in detail wherein for the purpose of illustration I have disclosed a preferred embodiment of the invention, the numeral 5 designates a conventional form of clothes wringer mounted at one side of a washing machine 6.

The wringer includes the usual drain board 7 under the rollers 8 of the wringer, the drain board projecting outwardly from opposite sides of the wringer.

Attached to each side of the drain board is an angle iron slide 9 including an inwardly projecting horizontal portion 10 adapted to support the outwardly turned flange 11 on the opposite side edges of a pan 12 to slidably support the pan

2

under the drain board of the wringer, the pan being adapted for movement into a position entirely under the board to prevent liquid from draining into the pan, or the pan may be moved outwardly at either end of the slide 9 and supported in the slide in an outwardly extended position as shown in Figure 2 of the drawings to permit clothes to be dipped into the starching liquid contained in the pan for starching the clothes and then to collect excess liquid from the drain board when the clothes are passed through the rollers of the wringer.

From the foregoing it will be apparent that the starching pan is conveniently placed with respect to the wringer so that the starching of certain garments, when desired, is facilitated.

It is believed that the details of construction and manner of use of the device will be readily understood from the foregoing without further detailed explanation.

Having thus described the invention, what I claim is:

An attachment for clothes wringers of a type including a drain board, said attachment being an angle iron slide attached to each side of the drain board, each slide including an inwardly projecting horizontal portion, and a pan adapted to contain liquid and having outwardly projecting flanges on its opposite sides slidably mounted on said slides to provide for sliding of the pan relative to said drain board, said pan being slideable beneath said drain board to completely close the same, and being slideable in opposite directions to project the same beyond said drain board into partially open position.

CLAUDE E. PICKENS.
